UNITED STATES PATENT OFFICE.

JOHN MACKENZIE, OF MINNEAPOLIS, MINNESOTA, ASSIGNOR OF ONE-HALF TO
WALTER HEYNACHER, OF MINNEAPOLIS, MINNESOTA.

GAS-HEATING SYSTEM.

Application filed May 22, 1925. Serial No. 32,124.

My invention relates to improvements in gas heating systems.

An object of the invention is to provide a simple and automatic heating appliance for use in connection with a furnace or other heater, said appliance being adapted to provide for the efficient combustion of the usual city gas or other gas supplied for heating purposes.

10 A further object is to supply a gas heating system, as above, the same including a blower driven by an electric motor for supplying air in admixture with gas at the burner and, also, including an electrically 15 actuated valve fitted in the gas line and connected in the motor circuit, whereby the flow of gas is arrested upon discontinuance of the supply of air from the blower, as by interruption of the motor circuit.

20 Another object is to provide a system of the instant character, wherein the motor circuit is interrupted and completed by an operating mechanism and a cut-off valve in the gas line is opened and closed by said 25 mechanism, said cut-off valve being adapted to be opened following the completion of the motor circuit, whereby motor speed may be gained for the supply of air in normal volume prior to the opening of the gas line 30 to the burner.

With the foregoing and other objects in view, which will appear in the following description, the invention resides in the novel combination and arrangement of parts and 35 in the details of construction hereinafter described and claimed.

In the drawings, Fig. 1 is a plan view of a heating system embodying my invention, parts thereof being shown more or less 40 diagrammatically; Fig. 2 is a sectional view taken as on the line 2—2 of Fig. 1 and illustrating certain parts of the appliance in elevation and other parts thereof diagrammatically and Fig. 3 is an elevational view, 45 broken away in part, illustrating certain details of the operating mechanism.

In Fig. 1 of the drawing, A designates a furnace or heater of conventional or suitable type such, for example, as is employed 50 in heating dwellings or other buildings. In the fire box 10 of the heater A, I place a burner 11 with which a main gas lead 12 is connected. A blower 13, driven by an electric motor 14, is connected by means of an 55 air lead 15 with the gas lead 12 through a

Y fitting 16, valve 17, 18 being respectively fitted in the gas and air leads 12, 15 immediately in advance of the Y fitting 16 to provide for adjusting the fuel mixture of gas and air delivered to the burner 11. 60

Were combustion at the burner 11 to be maintained without variation or interruption, that part of the appliance described would serve without any addition thereto. It is necessary, however, in heating dwellings or other buildings to vary the consumption of fuel at the burner to accord with the various conditions and it has been found that the most efficient practice resides in operating the burner "full on" to attain 70 the desired temperature and then extinguish the flame at the burner until such time as additional heat is required. A cut-off valve 19 of ordinary pattern, fitted in the gas lead 12, includes a lever 20 for lifting and 75 depressing the valve stem 21, through which stem the valve is correspondingly opened and closed. Said lever 20 is supplied with a weight 22 for lowering the same and has connected thereto a chain 23 for 80 raising said lever against the action of said weight 22. This chain 23 is fastened to an arm 24 on the shaft or prime mover 25 of a suitably driven operating mechanism B of conventional type, which may be actuated 85

by a conventional thermostatic device C located in the heated space. Generally illustrative of such conventional thermostatic devices and of such conventional operating mechanism, without the built in switch members 26 and 27, are the disclosures in Letters Patent of the United States No. 1,162,372, Nov. 30, 1915 to J. C. Kersteter for motor and No. 1,167,890, Jan 11, 1916 to F. S. Denison for electric motor, both assigned 90 to Minneapolis Heat Regulator Co. In the response of the operating mechanism B to each actuation of the thermostatic device C, the shaft 25 is turned one-half revolution, the valve 19 being thus opened at a 100 pre-determined minimum temperature in the heated space and closed at a predetermined maximum temperature therein. Since it is desirable that the operation of the blower 13 be discontinued when the valve 19 is closed, I provide, in conjunction with the operating mechanism B, a pair of complementary switch members 26, 27, the same being incorporated in the conductor 28 of the motor circuit. The switch members 26, 110

27 are brought into contact by the operating mechanism B, through the medium of a cam d on shaft 25, or other suitable means, to complete the motor circuit when the valve 19 is opened. This cam d provides for the separation of said members 26, 27 by the operating mechanism B to interrupt the motor circuit when said valve 19 is closed by said mechanism. Although the switch 10 members 26, 27 and the valve 19 are operated by the mechanism B, it will be understood that there is a delayed action in the opening of said valve following the closing of said switch members. This delayed action may 15 be brought about in any suitable manner such as the provision of slack in the chain 23. With the opening of the valve 19 following the closing of the switch members 26, 27, the blower driving motor 14 is given 20 time in which to attain its normal speed before gas is permitted to pass the control valve 19 in the main gas lead 12. This arrangement is important in that it insures the introduction to the burner 11 of an 25 initial "lean" mixture rather than an initial "rich" mixture, the former having the advantage of clean and noiseless ignition as opposed to popping ignition and carbonizing combustion in the latter.

30 The motor 14, taking its current from the usual power lines, is subject to unpremeditated cessation of operation due to accidental interruptions in the flow of current thereto. The cessation of operation of the 35 motor 14 and its connected blower 13, when the cut-off valve 19 is open, would result detrimentally in the burning of pure gas at the burner 11 were it not for a safety valve 29 that is employed in the gas lead 12 in advance of said cut-off valve 19. This safety valve 29 has a fulcrumed lever 30 connected with the valve stem 31. A weight 32 on said lever 30 operates to close the valve and an armature core 33 depending from the lever 30 and hanging in a solenoid winding 34 operates to open said valve 29 against the action of said weight. Said solenoid winding 34 being incorporated in the conductor 35 of the motor circuit, it 45 will be understood that the energization thereof, upon completion of the motor circuit, will result in the attraction of the armature core 33 and the consequent opening of the valve 29 and that the deenergization of said winding, upon the breaking of the motor circuit, will allow the weight 32 to retract the armature core 33 and thereby cause the closing of the valve 29.

50 Taking off from the main gas lead 12 at a point in advance of the safety valve 29 and rejoining said lead at a point between the mixing valve 17 and burner 11 is a shunt pipe 36, the same being fitted with spaced cut-off valves 37, 38 and also with 55 a mixer valve 39 interposed between said cut-off valves. Branching from the shunt pipe 36 at a point in advance of said assemblage of valves 37, 38 and 39 is a pilot feed pipe 40, the same having a pilot fitting 40^a at the tip thereof for the burner 11 and also 70 being provided with a valve 41 for adjusting the flame issuing from said pilot fitting 40^a. Gas flowing from the main gas lead 12 into the shunt pipe 36 and thence into the pilot feed pipe 40 provides for a continuous 75 pilot flame at the burner 11 regardless of the setting of the valves 17, 19 and 29 in the main gas lead. Under ordinary circumstances the valves 37, 38 in the shunt pipe 36 are closed, but under emergency, when 80 the blower 13 cannot be operated, the valves 17, 18 in the gas and air leads 12, 15 are closed and said valves 37, 38 opened to permit of combustion at the burner 11 of gas mixed with air at atmospheric pressure. 85

In the operation of the appliance, the safety valve 29 opens upon completion of the motor circuit by the operating mechanism B and closes upon the interruption of said circuit by said mechanism or otherwise. Opening after the motor circuit has been completed by the operating mechanism B, the cut-off valve 19 holds back the flow of gas to the burner 11 until air passes in normal 90 volume from the blower 13 to said burner. 95

Changes in the specific form of my invention, as herein disclosed, may be made within the scope of what is claimed without departing from the spirit of my invention.

Having described my invention, what I 100 claim as new and desire to protect by Letters Patent is:

1. The combination with a heater of a burner therein, a gas lead connected with said burner, two cut-off valves fitted in said gas lead, one a mechanically operated valve and one an electrically operated valve, a blower for delivering air into the gas lead at a point between said burner and valves, an electric motor for driving said blower, 105 an electric circuit common to the motor and the electrically operated valve, operating mechanism acting to break and complete said circuit and to correspondingly close and open said mechanically actuated valve, said 110 electrically operated valve being adapted automatically to close upon cessation of the flow of current through said circuit, as through the operation of said mechanism or otherwise, the opening of said mechanically 115 operated valve, upon the completion of said circuit by said operating mechanism, being attended with delay to allow for the pick up of speed in the motor prior to the opening of said gas lead by said valve. 120

2. The combination with a heater of a burner therein, a gas lead connected with said burner, a valve in said gas lead, a blower, an air lead for conducting air from the blower to the gas lead at a point between 125 130

said valve and burner, a valve in said air lead, a shunt pipe for conveying gas to the burner, said pipe being connected with the gas lead at a point in advance of the valve 5 therein, spaced cut-off valves fitted in said shunt pipe, and an air admission valve fitted in said pipe between said cut-off valves.

3. The combination with a heater of a burner therein, a gas lead connected with 10 said burner, a valve in said gas lead, a blower, an air lead for conducting air from the blower to the gas lead at a point between said valve and burner, a valve in said air lead, a shunt pipe for conveying gas to the 15 burner, said pipe being connected with the gas lead at a point in advance of the valve therein, spaced cut-off valves fitted in said shunt pipe, and an air admission valve fitted in said pipe between said cut-off valves, and 20 a pilot feed pipe associated with said burner and connected with the shunt pipe at a point in advance of the first cut-off valve in said shunt pipe.

4. The combination with a heater of a 25 burner therein, a gas lead connected with said burner, a cut-off valve fitted in said gas lead, a blower for delivering air into the gas lead at a point between said valve and burner, an electric motor for driving said 30 blower, said motor having an electric circuit therefor including a switch for making and breaking said circuit, an operating mechanism common to said switch and valve, a thermostatic device responsive to temperatures in the heated space, said device being 35 adapted to actuate the operating mechanism, said mechanism having an independent source of power and comprising promptly operative means for closing the motor circuit and delayed operative means for opening the gas valve, all in one operation, said 40

means serving also to close the valve and open the switch in another operation.

5. The combination with a heater of a burner therein, a gas lead connected with 45 said burner, a cut-off valve fitted in said gas lead, a blower for delivering air into the gas lead at a point between said valve and burner, an electric motor for driving said blower, said motor having an electric 50 circuit therefor including a switch for making and breaking said circuit, an operating mechanism common to said switch and valve, a thermostatic device responsive to temperatures in the heated space, said device being 55 adapted to actuate the operating mechanism, said mechanism having an independent source of power and comprising promptly operative means for closing the motor circuit and delayed operative 60 means for opening the gas valve, all in one operation, said means serving also to close the valve and open the switch in another operation, and means separate from the above mentioned means for shutting off the 65 gas supply when the motor circuit is interrupted.

6. The combination with a heater of a burner therein, a gas lead connected with 70 said burner, a valve in said gas lead, a blower, an air lead for conducting air from the blower to the gas lead at a point between said valve and burner, a cut-off valve in said air lead, a shunt pipe for conveying gas 75 to said burner connected with the gas main at a point in advance of said valve therein, and means for supplying air to the burner in conjunction with said shunt pipe.

In testimony whereof, I have signed my name to this specification.

JOHN MACKENZIE.
